FIG. 1

FIG. 2

FIG. 3

UNITED STATES PATENT OFFICE

2,207,178

ANGLE TILE

Albert A. Richards, Montebello, Calif.

Application January 4, 1939, Serial No. 249,268

6 Claims. (Cl. 72—18)

My invention relates to angle tile and among the objects of my invention are:

First, to provide an angle tile which without change in the glazed surfaces may be used interchangeably as a base or cove element, cap or bead element, internal angle element, or external angle element; thus providing an angle tile which performs the functions formerly requiring several different shapes and differently glazed angle tile, and correspondingly reducing the stock required by the tile setter.

Second, to provide an angle tile which is provided with ample unglazed surface so shaped to insure adequate bond with the backing cement.

Third, to provide an angle tile which may be used harmoniously in conjunction with a wide variety of wall and floor tile patterns.

With the above and other objects in view as may appear hereinafter reference is had to the accompanying drawing in which:

Figure 1 is a fragmentary perspective view of a tile wall employing my special angle tile.

Figure 2 is a perspective view of the angle tile per se.

Figure 3 is an enlarged fragmentary sectional plan view of a tile wall illustrating the use of my tile for internal and external angles, the view being taken through 3—3 of Fig. 1.

Figure 4 is an enlarged fragmentary vertical sectional view of a tile wall illustrating the use of my tile for coves and beads.

Figure 5 is a perspective view of a corner tile which may be used as a companion piece with my angle tile.

My angle tile consists essentially of a central body portion 1 and flanking marginal wing portions 2, each disposed at a forty-five degree angle with the body portion. The outer surfaces of the body portion and wing portions are glazed as indicated by 3 and 4 respectively. The edge 5 of each wing portion is equal in thickness to a standard tile and the width of each wing portion at its outer, glazed side between its edge 5 and the body portion 1 is likewise equal in thickness to standard tile.

The body itself is approximately the thickness of the wing portions so that the rear or inner side of the tile is provided with three faces 6 forty-five degree angles with each other. The faces 6 and the edges 5 are unglazed, thus five of the eight faces comprising the tile are unglazed for binding association with the backing cement.

Application of the angle tile is best observed in Figs. 3 and 4. In the latter figure the angle tile is shown in use as a base or cove tile 11 and

a cap or bead tile 12. When used as a base tile the body surface 3 is the only exposed surface, the glazed surfaces 4 of the wing portions confronting the edges of floor tile 13 and wall tile 14. While these surfaces 4 provide poor bond with the cement 15, the faces 6 and edges 5 are ample to insure proper bond and further the angle tile is completely keyed by the adjacent tile.

When used as a cap or bead tile 12, all three 10 glazed surfaces may be exposed or, as shown, tile 16 may continue from the upper wing.

With reference to Fig. 3, when the angle tile is used to form an internal angle as indicated by 17, the relationship with adjacent wall tile 15 14 is the same as with the floor tile 13 and wall tile 14 of Fig. 4, the corner tile being both cemented and keyed in position. When used to form an external angle as indicated by 18 all five surfaces 5 and 6 are available to firmly bond 20 the tile with the backing cement 15.

It will be observed that not only may the angle tile take the same form for the different positions 11, 12, 17 and 18, but the same surfaces are glazed in each case; this materially reduces 25 the stock of angle tile that must be carried or supplied for a job. This is made possible by the particular relationship between the body portion and flanking wing portions 2 and the equal proportions of the glazed surfaces 4 and edges 30 5. Furthermore by making the body portion 1 flat and at a forty-five degree angle, the internal angles and base corners are easily cleaned, any other shape of the body portion such as a convex arc would form two hard-to-clean corners; 35 whereas a concave arc would be unsightly for use as cap or external angle tile.

The advantages and adaptability of the angle tile apply to companion pieces such as the corner tile 21 shown in Fig. 5 in which the triangular 40 portion 22 corresponds to the body 1 and the flanking portions 23 aline with the body portions of the tile 18 and 12 when used to form an external corner 24 or abut tile 17 and 11 when used as an internal corner 25. As with 45 the angle tile, only the surfaces shown in Fig. 5 need be glazed for either use.

Corner tile for the corners indicated by 26 and 27, however cannot be interchanged although the same form may, by glazing different 50 sides, be used.

Though I have shown and described certain embodiments of my invention, I do not wish to be limited thereto but desire to include in the scope of my invention, the construction, combi- 55

nations and arrangements as embraced in the appended claims.

I claim:

- 5 1. An angle tile comprising a body portion and flanking wing portions each set at a forty-five degree angle therewith, the wing portions adapted to occupy interchangeably an abutting or continuing relation with adjacent tile, one surface each of said body portion and said flanking wing portions being glazed.
- 10 2. An angle tile comprising a body portion and flanking wing portions each set at a forty-five degree angle therewith, the wing portions being approximately equal in width and thickness forming edges, said edges and said wing portions adapted to be employed interchangeably in abutting relation with adjacent tile forming a wall or floor, one side of said body portion and said flanking wing portions constituting the convex or outer side of said tile, and a glaze covering for said surface.
- 15 3. A tile as specified in claim 2 wherein the body portion is flat and when the tile is in position forms an internal or external beveled corner depending on the location of the angle tile.
- 20 4. An angle tile adapted to form interchangeably a beveled corner between right-angularly disposed wall surfaces or wall and ceiling or floor surfaces, said angle tile being substantially uni-

form and of standard tile thickness and having an outer side comprising a middle body portion with flanking wing portions disposed at forty-five degree relationship, the width of said flanking portions being substantially tile thickness whereby said flanking portions or the edges of the angle tile may be disposed in abutment with standard tile, said angle tile being glazed on said outer side only.

5 5. A tile as specified in claim 2, the body portion only being exposed when said wing portions are in abutting relation with adjacent tile and the wing portions as well as the body portion are exposed when the edges are in such abutting relation.

10 6. An angle tile comprising: an elongated rectangular body portion and flanking wing portions along the two longer sides of said body portion and set at a forty-five degree angle therewith, the wing portions being approximately equal in width and thickness forming edges, said edges and said wing portions adapted to be employed interchangeably in abutting relation with adjacent tile forming a wall or floor and a glazed surfacing on the normally outer side only of said body portion, and the corresponding surfaces only of said wing portions.

15 20 25 ALBERT A. RICHARDS.
